UNITED STATES PATENT OFFICE

RALPH R. KEMMERER, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY TRAFFIC CONTROLLING APPARATUS

Application filed October 3, 1930, Serial No. 486,103. Renewed February 6, 1932.

My invention relates to railway traffic controlling apparatus for utilizing periodically interrupted or coded current in track circuits for the control of either or both wayside signals and train carried cab signals, and more particularly it relates to apparatus for utilizing coded current in the running rails in connection with a controlled manual block system.

10 I will describe one form of apparatus embodying my invention, and will then point out the novel features thereof in claims.

The accompanying Figs. 1^a, 1^b, 1^c and 1^d, when placed end to end in the order named, 15 with Fig. 1^a on the left, form a diagrammatic view showing one form of apparatus embodying my invention for a stretch of track which includes three signal locations. Fig. 2 is a diagrammatic view illustrating a form of 20 coded current that may be used in the track circuits of my invention. Fig. 3 is a view showing the rate of operation of the several contacts of each code transmitter CT shown in Figs. 1^b to 1^d.

25 In describing my invention, reference is made to the accompanying figures wherein like characters of reference designate corresponding parts, an exponent being added to certain reference characters to 30 designate the locations of the parts. In this description, I shall assume the left-hand end of Figs. 1^a, 1^b, 1^c and 1^d to be west, and the right-hand end of each figure to be east, and I shall speak of a train traveling from the 35 right to the left as a westbound train and one traveling from the left to the right as an eastbound train.

In the Figs. 1^b, 1^c and 1^d, the reference characters 1 and 2 designate track rails over 40 which traffic may move in either direction. These rails are arranged in track sections A—B, B—C, etc., by the usual insulated rail joints. In Fig. 1^a is shown a manually operable lever N which is located at some convenient point such as at one end of the stretch of track and which may be a part of an interlocking machine, and which also may or may not be electrically locked with a lever of a second machine located at the opposite 45 end of the stretch in any of the numerous 50

arrangements of traffic locking circuits that are used for that purpose.

Energy for the operation of the track apparatus and the wayside signals is furnished by line transformers L one of which is located at each junction of adjacent track section. The primary 4 of each of these transformers is connected to a transmission line E, which is constantly supplied with alternating current of a convenient commercial frequency such as 60 cycles per second from a source not shown in the figures. Energy for a directional control line circuit is supplied by a battery X shown in the Fig. 1^a.

An auxiliary transformer M is located at each junction of adjacent track sections and its primary 5 is supplied with current from the secondary 6 of the associated line transformer L. A secondary 7 of each auxiliary transformer M is connected to the input terminals of a rectifier R which furnishes direct current for the operation of certain parts of apparatus of my invention.

Located at each junction of adjacent track sections is a directional relay FR and two repeater relays WR and ER and the direction of traffic is established by the position of the directional relay FR. The control of the directional relays is by means of the manual control lever N over the directional control circuit which includes the line wires 33 and 34, across which the several directional relays of the system are connected in parallel. With the lever N set in its normal position, that is, the position as shown in solid lines in 85 the Fig. 1^a, this directional control circuit extends from the positive terminal of the battery X to wire 35, controller contact 36 operated by lever N and normally closed, wire 33, wire 37, directional relay FR^a, wire 38, wire 34, controller contact 39 normally closed, and wire 40 to the negative terminal of the battery X. As stated above, current is also supplied to each of the several directional relays of the system by this same circuit. The 90 polarity of the normal current is such that the polar armatures of each of the directional relays occupy the left-hand position, that is, the position as shown in the figures. With the control lever N reversed to the position 95 100

shown by the dotted lines, the positive terminal of the battery X is connected to the line wire 34 by a controller contact 41 which is closed with lever N reversed, and the negative terminal of the battery X is connected to the line wire 33 by a controller contact 42 which is closed with the lever N reversed; therefore the current supplied to the directional relays is reversed and the polar armatures of each of these relays are swung to the right-hand position. Looking at location B of Fig. 1^c, the circuit for energizing the westbound repeater relay WR^B is from the positive terminal of rectifier R^B, wire BX, front contact 43, normal polar contact 44, wire 45, back contact 46 of repeater relay ER^B, wire 47, relay WR^B, and wires 48 and CX to the negative terminal of rectifier R^B. With the directional relay FR^B energized with reverse polarity of current then the eastbound repeater relay ER^B is energized, the circuit being from positive terminal of rectifier R^B, wire BX, front contact 43, reverse polar contact 49, wire 50, back contact 51 of relay WR^B, wire 52, relay ER^B, and wires 48 and CX to negative terminal of R^B.

Each track section is provided with a track circuit which includes two track transformers designated by the reference characters T1^B and T2 and a track relay designated by the reference character TR. Looking at the track section B—C and considering first the normal active track transformer T1^B, the secondary 8 of said transformer has one terminal connected to rail 2 by current limiting reactor 10, wire 11, rectifying device 12 furnishing half-wave rectification, and wire 13, and its other terminal connected to the rail 1 of the section by the wire 14. Considering next the normally inactive transformer T2^C of the section B—C, the secondary 15 of this transformer has one terminal connected to the rail 1 by wire 16, reactor 17, wire 18, rectifying device 19, and wire 21, while the other terminal is connected to the rail 2 by the wire 20. With the direction of traffic set for westbound traffic, which is the normal position of the apparatus and that shown in the figures, the primary 22 of the track transformer T1^B is supplied with alternating current from the associated line transformer L^B which current is periodically interrupted or coded at the rate of 80, 120 or 180 cycles per minute, or any other code frequency desired, as determined by traffic conditions, as will be fully described later on in the specification. Whenever the direction of traffic is set for westbound traffic, the primary 23 of track transformer T2^C is on open circuit and thus no energy is supplied by its secondary to the rails of the section. With the reversal of the direction of traffic, then coded energy is fed to the primary 23 of the track transformer T2^C and it becomes active to supply coded current to the rails of the section, and the

primary 22 of the track transformer T1^B is on open circuit, as will be fully described later on.

With the primary 22 of the normal feeding transformer T1^B supplied with periodically interrupted or coded alternating current and inasmuch as the rectifier 12 furnishes half-wave rectification, it follows that normally the track rails of the section B—C are supplied with a coded pulsating or unidirectional current from the alternating current transmission line E. In Fig. 2, the diagram "a" is a representation of the usual form of the 60 cycle alternating current of the transmission line. The diagram "b" shows the current in the primary of the track transformer during the "on" and "off" periods of 120 code current, while the diagram "c" represents the half-wave impulses that flow in the track rails during the "on" period of the 120 cycle code.

The track relay TR of each section is a two element relay, the control element 24 of which (see relay TR^C) is connected normally to the rails of the section at the end opposite the normally active transformer T1^B in the following manner: wire 25, front contact 26 of a relay WR^C, and wire 20 to the rail 2. The opposite terminal of element 24 is connected through wire 27, front contact 28 and wire 21 to the rail 1 of the section B—C. That is to say the control element 24 of each track relay is normally connected to the rails at the end opposite that at which they are normally supplied with coded unidirectional current. The second element 29 of the track relay is continuously supplied with rectified alternating current through the medium of the wires BX and CX which are connected to the positive and negative output terminals of the full-wave rectifier R^C. The characteristics of the track relay are such that each will attract its armature 30 into engagement with the front contact 31 during the "on" period of a code cycle, and will release armature 30 to drop into engagement with the back contact 32 during the "off" period of each code cycle. It follows, therefore, that, with the track relay TR^C operated by coded unidirectional current of any of the codes 80, 120 or 180, the armature 30 is in engagement with its front contact 31 and back contact 32 alternately at the rate of 80, 120 or 180 times per minute. It has been pointed out that normally the track element 24 of each track relay is connected to the rails of the track section at the right-hand end, that is, at the entrance end of the block for westbound traffic. With eastbound traffic established by the control lever N being reversed, and the eastbound repeater relay ER at each location energized, and the westbound repeater relay WR de-energized, then the control element 24 of the track relay is disconnected from the right-hand end of each section at the contacts 28

and 26 of the westbound relay WR and is connected to the left-hand end of the adjacent track section, that is, it is connected to the entrance end of a track section for eastbound traffic. Looking at track relay TR^c , the element 24 is connected to the rails of the section to the right of location C by wires 25 and 53, front contact 54 of the relay ER^c and wire 55 to the rail 1, while the other terminal 10 of the element 24 is connected by wires 27 and 56, front contact 57 and wire 58 to the rail 2.

Each track relay controls decoding apparatus including a decoding transformer DT and three decoding relays H, D and DR, in such a manner that these relays are selectively responsive to operation of the track relay at the three code rates specified. The primary 59, (see location A) of the decoding transformer DT^A is supplied with direct current 20 by the associated rectifier R^A . With the associated track relay TR^A energized so that armature 30 is in engagement with contact 31, current flows from the positive terminal of rectifier R^A , along wire BX, armature 30, 25 front contact 31, right-hand half of the primary 59, to a center tap, and then wire CX to the negative terminal of RA. When the track relay TR^A is deenergized and armature 30 is in engagement with the back contact 32, the current from rectifier R^A flows through 30 the left-hand half of the primary 59. It follows then that with the track relay TR^A operated with coded current and its armature 35 alternately in engagement with front contact 31 and back contact 32, an alternating voltage is induced in the secondary 60 of the transformer DT^A , the frequency of which is the same as the frequency of operation of the track relay, but with the track relay TR^A 40 continuously energized or continuously deenergized no voltage is induced in the secondary 60.

The secondary 60 has one secondary circuit connected to the input terminals 45 of the rectifier 61 through a reactor 62, while the output terminals of the rectifier 61 are connected to the decoding relay H^A . This secondary circuit being non-tuned, it follows that with track relay TR^A being 50 alternately energized and deenergized in step with either the 80 code, 120 code or 180 code, the relay H^A is energized, but with the track relay remaining continuously energized or deenergized, the decoding relay H^A is deenergized. The secondary 60 has a second 55 secondary circuit including reactor 63 in series with the condensers 64 and 65 connected in multiple, while the input terminals of the rectifier 66 are connected across a portion of the reactor 63. The decoding relay D^A is 60 connected to the output terminals of the rectifier 66 and the parts of this secondary circuit are so chosen that the relay D^A is energized only when the track relay TR^A is operated by 120 code current. The secondary 65

has a third secondary circuit, which includes a reactor 67 and a condenser 68 in series, while the input terminals of a rectifier 69 are connected across a portion of the reactor 67. The decoding relay DR^A is connected to the output terminals of the rectifier 69 and the parts of this circuit are so chosen that the decoding relay DR^A is energized only when the track relay TR^A is operated by 180 code current. A condenser 70 may be connected 70 across the terminals of the primary 59 to reduce the sparking at the contacts 31 and 32.

At the junction of each adjacent track section there is provided a code transmitter 75 designated by the reference character CT with an exponent designating its location. Each code transmitter includes a motor element 71 constantly supplied with current by the rectifier R as will be readily understood by an inspection of the drawings. This code transmitter is to be of any of the standard types commonly used in code systems, and, as here shown, it will be understood that the upper contact 72 is periodically closed at the rate of 180 times per minute, that the center contact 73 is periodically closed at the rate of 120 times per minute, and that the lower contact 74 is periodically closed at the rate of 80 times per minute.

Each track section is provided with a wayside signal located at each end of the section to govern traffic in opposite directions through the section. Signals governing westbound traffic are designated by the reference character 1S with an exponent to designate the location, and signals governing eastbound traffic are designated 2S plus a proper exponent. These wayside signals may be of any of the well known types which are capable of displaying four indications but, as here shown, each wayside signal comprises two groups of lamps K and P. Group K comprises a green lamp G, a yellow lamp Y and a red lamp R. Group P comprises a green lamp G and a red lamp R. The lamps of each signal are controlled by the decoding relays of the corresponding location in a manner which will be described hereinafter.

Associated with the wayside signals at each location is an approach lighting relay 110 designated by the reference character AR. This relay is controlled by the track relay at the location to the rear. Looking at relay AR^B , we find that under normal conditions, 115 that is, when westbound traffic is established, the circuit to energize relay AR^B extends from the positive terminal of rectifier R^c , wire BX, wire 87, front contact 88 of decoding relay H^c , wire 89, front contact 90 of relay WR^c , line wire 91, back contact 92 of the relay ER^B , coil of the relay AR^B , wire 93, front contact 94 of the decoding relay H^B , wire CX, line wire 34, and the CX wire at location C to the negative terminal of the rectifier R^c . With a reversal of traffic then 120

this approach lighting relay AR^B is energized by a circuit which extends from the positive terminal of rectifier R^A , wire BX, wire 95, front contact 96 of the decoding relay H^A , wire 97, front contact 98 of relay ER^A , relay ER^A now being energized, line wire 99, back contact 100 of relay WR^B , relay AR^B , wire 93, front contact 94, wire CX, line wire 34, and the CX wire at location A to the negative terminal of the rectifier R^A .

Looking at signal $2S^B$ for illustration, the G lamp of group K is supplied with current from the secondary 6 of transformer L^B over wire BX110, back contact 126 when approach lighting relay AR^B is deenergized, wire 127, front contact 222 of relay ER^B , this relay having been energized by the selecting of eastbound traffic, front contact 130 of relay H^B , front contact 223, lamp G and the return wire CX110. With the 180 code decoding relay DR^B down then the Y lamp is supplied by the above circuit over back contact 132 and wire 133. The R lamp of group K of signal $2S^B$ receives current from secondary 6 of L^B by back contact 126, wire 127, back contact 194 of ER^B and wire 221, or by the back contact 224 of H^B and wire 221 when relay ER^B is energized. The G lamp of group P of $2S^B$ receives current from secondary 6 by a circuit branching from wire 127 to front contact 225, front contact 134, wire 135, back contact 136, front contact 226 with 120 code decoding relay D^B energized, and wire 227. The R lamp of group P receives current by a circuit branching from wire 127, over front contact 225, front contact 134, wire 135, front contact 228 of DR^B and wire 138, or with ER^B down then by back contact 192, or with both relays D^B and DR^B down by the back contacts 136 and 137.

Having pointed out the several devices with which each track section is provided, I shall now describe the operation, and I shall first assume that all track sections are unoccupied and that the direction of traffic established is for westbound trains. With the control lever N set at normal position so that the directional relay at each signal location occupies its normal position, that is, the position as shown in the figures, and with the westbound repeater relay at each location energized, a track relay TR is connected to the rails at the right-hand end of each section as was heretofore pointed out. Under this normal condition, the primary 22 of each track transformer $T1$ is supplied with 180 code alternating current by a circuit which includes one terminal of the secondary 6 of the associated line transformer L , (see location B) wire 75, 180 code contact 72 of the code transmitter CT^B , wire 76, front contact 77 of decoding relay DR^B , wire 78, back contact 79, wire 80, front contact 81 of decoding relay H^B , wire 82, front contact 83 of the repeater relay WR^B , wire 84, primary 22, and

the CX110 wire to the other terminal of the secondary 6. It follows that with 180 code alternating current supplied to the primary 22, the secondary 8 feeds 180 code alternating current to the track circuit of section B-C, but due to rectifier 12 furnishing half-wave rectification, the current supplied to the rails becomes 180 code pulsating or unidirectional current. Thus, under the normal position of the control lever N, a track relay is connected at the right-hand end of each section and 180 code unidirectional current is supplied to the rails at the left-hand end of each section, that is, at the leaving end for westbound traffic. Hence 180 code current operates the track relay and the decoding relays H and DR at each location are normally energized.

Assuming the control lever N to be set in its reverse position, the reversal of the directional relay at each location will deenergize the repeater relay WR and energize the repeater relay ER . Looking at location B, we find that this will disconnect the track element 24 of the track relay TR^B from the rails of the section A-B at the front contacts 188 and 189 of the relay WR^B , and will connect element 24 to the rails of the section B-C by means of the front contacts 190 and 191 of the repeater relay ER^B . Also the circuit to feed coded energy to the primary 22 of track transformer $T1^B$ is opened at front contact 83 of relay WR^B and coded energy is now fed to the primary 23 of the track transformer $T2^B$ by a circuit which extends from one terminal of secondary 6 of line transformer L^B , wire 75, 180 code contact 72 of CT^B , wire 76, front contact 77 of decoding relay DR^B , wire 78, back contact 79, wire 80, front contact 81, wire 82, front contact 85 of repeater relay ER^B , wire 86, primary 23, and wire CX110 to the other terminal of the secondary 6. Due to the rectifier 19 the current supplied to the rails of track section A-B by its secondary 15 is 180 code unidirectional current. Thus with eastbound traffic established, the track relay is now connected to the left-hand end of each section, that is, the entrance end for eastbound traffic, and each track transformer $T2$ supplies 180 code energy to the rails at the right-hand end of each section, which is, the exit end for eastbound traffic, and the decoding relays H and DR are energized.

By supplying coded energy to the rails at the exit end of each track section for either direction of traffic and by transferring the connection of the track relay to the entrance end of each track section, said relay being responsive to such coded energy, there is provided trackway apparatus that operates the wayside signals. This coded energy may also be used for the control of train carried apparatus receiving current inductively from the rails such, for example, as the apparatus

disclosed and claimed in Letters Patent of the United States, No. 1,773,472, filed by P. N. Bossart on the 7th day of February, 1927.

I shall now describe the operation for a westbound train. The operator places the control lever N at normal and the track apparatus will then assume its normal position, that is, the position as shown in the figure. A train entering the section to the right of location C and thereby shunting the track relay of that section will open the circuit to the approach lighting relay AR^c at the location to the right of location C. With the relay AR^c down and inasmuch as the track sections in advance are each unoccupied, a circuit is established for the green lamp G of group K of the wayside signal 1S^c as follows: secondary 6 of line transformer L^c, wire BX110, back contact 101 of relay AR^c, wire 102, front contact 9 of WR^c, wire 196, front contact 197 of relay H^c, front contact 198 of relay DR^c, wire 199, green lamp G of group K, and the CX110 wire to the common terminal of secondary 6. Also branching from the wire 102 there is a circuit over contact 103, wire 104, front contact 200 of relay H^c, wire 201, front contact 202 of DR^c, wire 203, red lamp R of group P, and the CX110 wire to the common terminal of secondary 6. It follows that the signal 1S^c will display a proceed signal by means of the green lamp G of the group K and the red lamp R of the group P to the train approaching from the east. As the train advances and enters each successive track section of the system, a proceed signal will be displayed at each westbound signal in a like manner.

Let us assume that the train advances westward and finally occupies the track section to the left of the location A. The track relay TR^a being shunted by the train, the decoding relays H^a, D^a, and DR^a will each be deenergized with the result that a circuit is established from secondary 6 of the line transformer L^a which includes wire BX110, back contact 113 of the approach lighting relay AR^a, assuming this relay to be deenergized as it will be if a second train approaches, wire 114, front contact 232, wire 193, back contact 119 of decoding relay H^a, wire 204, red lamp R of group K of the signal 1S^a, and wire CX110 to the common terminal of secondary 6. Also a circuit is established which branches from wire 114 to front contact 115, wire 116, back contact 205, wire 206, to the red lamp R of group P of signal 1S^a, and to the common terminal of secondary 6. The signal 1S^a, therefore, displays a stop indication by the red lamp R of group K and the red lamp R of group P indicating that the immediate track section in advance is occupied.

Furthermore, by virtue of the decoding relays H^a, D^a and DR^a all being deenergized, 80 code energy is fed to the primary 22 of the track transformer T1^a, the circuit being from

the secondary 6, along wire BX110, 80 code contact 74 of CT^a, wire 121, back contact 122, wire 123, front contact 124, wire 125, primary 22, and the CX110 wire to the common terminal of secondary 6. The result of 80 code energy being supplied to the primary 22 of the track transformer T1^a is that the track relay TR^b is operated on 80 code and the decoding relay H^b energized but both the decoding relays D^b and DR^b remain deenergized. At location B, the circuit to the signal 1S^b is from the secondary 6 of the line transformer L^b, along wire BX110 back contact 126 of the approach lighting relay AR^b, wire 127, front contact 207, wire 208, front contact 209, wire 210, back contact 211 of decoding relay DR^b, wire 212, yellow lamp Y of group K, and wire CX110 to the common terminal of secondary 6. Also branching from the wire 127, a circuit extends through front contact 128, wire 129, front contact 213, back contact 214, back contact 215, wire 195, red lamp R of group P, and the CX110 wire to the common terminal of secondary 6. Thus to any train approaching the signal 1S^b there is displayed a yellow lamp of the group K and a red lamp of the group P indicating that the first track section in advance is unoccupied but that the second section in advance is occupied. With decoding relay H^b energized, 120 code current is supplied to the secondary 22 of track transformer T1^b, the circuit extending from the secondary 6 of line transformer L^b, wire BX110, 120 code contact 73 of CT^b, wire 139, back contact 140, wire 78, back contact 79, wire 80, front contact 81, wire 82, front contact 83, wire 84, primary 22, and the CX110 wire to the common terminal of secondary 6. The result is that the track relay TR^b is now operated on 120 code and the decoding relays H^b and D^b are energized while the decoding relay DR^b is deenergized. At location C, we find that the circuit for the signal 1S^c is now from the secondary 6, along wire BX110, back contact 101 of the approach lighting relay AR^c, wire 102, front contact 9, wire 196, front contact 197, back contact 216, wire 217, lamp Y of group K, and wire CX110 back to secondary 6. Also branching from wire 102, a circuit extends through the front contact 103, wire 104, front contact 200, back contact 218, front contact 219 of the decoding relay D^c, wire 233, green lamp G of group P of the signal 1S^c, and wire CX110 back to secondary 6. Thus signal 1S^c displays a yellow light of the group K and a green light of the group P indicating to an approaching train that both the track sections B—C and A—B are unoccupied but that the section to the left of location A is occupied. With the decoding relays H^c and D^c energized, 180 code energy is supplied to the secondary 22 of the track transformer L^c by a circuit that includes the secondary 6, wire BX110, 180 code contact 72 of CT^c, wire 147, front con-

tact 148, wire 149, front contact 150, wire 151, front contact 152, wire 153, secondary 22, and wire CX to the common terminal of secondary 6. With the rails of the section to the right of location C thus supplied with 180 code current normal conditions will exist at the next section to the left of section B—C. It is to be noted that as a westbound train advances through the successive track sections the opposing eastbound signal at each location displays a stop signal. Taking location B, for example, with the approach lighting relay AR^b shunted by the westbound train, a circuit exists for the red lamp R of group K of the signal 2S^b which circuit branches from the wire 127 and extends through the back contact 192 of relay ER^b, wire 138, red lamp R of group P to the common wire CX110. Also branching from wire 127 is a circuit which extends through the back contact 194, wire 221 to the red lamp R of group K of signal 2S^b and to the common wire CX110.

In view of the fact that a train occupying the track section to the left of location A sets up a condition whereby 80 code current is supplied to the rails at the exit end of section A—B, 120 code current is supplied to the rails at the exit end of the section B—C and 180 code current is supplied to the rails at the exit end of the section to the right of location C. It becomes apparent therefore that the trackway apparatus here shown may be used for the control of train carried cab signals such as disclosed in the U. S. Letters Patent 1,773,472, heretofore mentioned, the cab signals displayed being duplicates of the wayside signals.

The operation for an eastbound train requires first that the control lever N be reversed to thereby reverse the directional relay FR, to energize the eastbound repeater relay ER and deenergize the westbound repeater relay WR in the manner previously described. After the direction of traffic is thus established, the operation of the system for an eastbound train travelling through the several successive sections is similar to that described for a westbound train. In the case of eastbound traffic, the track transformer T2 is supplied, in each case, with coded current in the same manner as the track transformer T1 is supplied with coded current for westbound trains, that is to say, that for eastbound traffic, the primary 23 of track transformer T2 is supplied with coded energy in a manner determined by traffic conditions to the right, in the same way as the supply of coded energy to the primary 22 of track transformer T1 was determined by traffic conditions to the left for westbound traffic. The decoding relays control the lamp circuits for the eastbound signals 2S in the same manner as they control the lamp cir-

cuits for the westbound signals 1S under westbound direction of traffic.

For illustration, in the event the FR relays are set for eastbound traffic and an eastbound train is approaching, let us say signal 2S^c, approach lighting relay AR^c being open current is supplied to the G lamp of group K over back contact 101, wire 102, front contact 229, front contact 105, wire 106, front contact 107 of relay DR^c in the event traffic conditions in advance of signal 2S^c are such that DR^c is energized, and wire 108. At the same time the R lamp of group P is energized by the circuit branching from wire 102, through front contact 230, front contact 109, wire 110, front contact 111 and wire 112. In the event relay DR^c is down and relay D^c energized, then the Y lamp of group K is energized over the above circuit for the G lamp up to back contact 141 and then by wire 142. Under this condition the Y lamp of group P is energized over back contact 143 of DR^c, front contact 145 of D^c and wire 146. In the event only the decoding relay H^c is energized, the Y lamp receives current as above traced and the R lamp of group P is energized by a circuit that includes back contact 143 of DR^c and back contact 231 of relay D^c.

The usual traffic locking circuit for the control lever N is provided in order that once the direction of traffic has been established and a train has accepted a signal, the operator cannot then change the direction of traffic as long as the train occupies any of the track sections of the stretch. The lock magnets 154 and 155 operate locking dogs 156 and 157, respectively, and these locking dogs 156 and 157 mate with latches 158 and 159 on quadrants 160 and 161 rigidly connected in the usual manner to the lever N. The lock magnets 154 and 155 are shown connected in parallel to a control circuit that includes contacts of the directional relays and the decoding relays at each location. This circuit may be traced as follows: positive terminal of a rectifier R^c, assuming location C to be the most eastwardly signal location of the stretch, wire 164, front contact 165 of the decoding relay H^c, wire 167, front contact 168 of directional relay FR^c, normal polar contact 169, back contact 170 of the repeater relay ER^c, front contact 171 of the repeater relay WR^c, line wire 172, front contact 173 of decoding relay H^b, front contact 174, polar contact 175, back contact 176, front contact 177, line wire 178, front contact 179, front contact 180, polar contact 181, back contact 182, front contact 183, line wire 184, magnets 154 and 155 in parallel, and the line wire 34 back to the negative terminal of the rectifier R^c. Furthermore, it will be noted that with a reversal of the direction of traffic that this control circuit then includes a reverse contact of the directional relay and a front con-

tact of the ER relay. Looking at location C for illustration, with relay FR^c reversed and repeater relay ER^c up then the control circuit for the lock magnets is from the front contact 168 by way of the reverse polar contact 185, front contact 186 of the relay ER^c, back contact 187 and to the line wire 172.

Such a system herein disclosed and described is practically immune from propulsion alternating current or direct current or any other form of electrical energy that may be used in the running rails. The track relays and the train governing means aboard the locomotive both respond readily to coded unidirectional current herein proposed thereby permitting the use of low energy output making such an arrangement desirable where the alternating current power is limited. While the disclosure shows a system fed directly from an alternating current transmission line, it will function equally as well for a system using a trickle charged storage battery and a tuned alternator as stand by apparatus to insure continuous operation of wayside and cab signals during periods of loss of power on the transmission line.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. In a combined wayside and cab signal system including, a stretch of track rails over which traffic may move in either direction, a wayside signal located at each end of the stretch to govern traffic in opposite directions through the stretch, a current source capable of supplying to the rails at either end of the stretch unidirectional current periodically interrupted which is adaptable to control train-carried cab signals, a track relay at each end of the stretch responsive to unidirectional current periodically interrupted, a manually controlled directional means for establishing the direction of traffic to connect the track relay to the rails at the entrance end of the stretch for the direction established, and to render the current source effective to supply said periodically interrupted current to the rails at the exit end of the stretch for the said direction of traffic, a decoding relay associated with each track relay, means to energize the decoding relay when the associated track relay is operated by said periodically interrupted current, and means controlled by said decoding relay to govern the operation of the signals.

2. In a combined wayside and cab signal system including, a stretch of track rails over which traffic may move in either direction, a

wayside signal located at each end of the stretch to govern traffic in opposite directions through the stretch, a current source capable of supplying to the rails at either end of the stretch unidirectional current 70 periodically interrupted at different rates which are adaptable to control train carried cab signals, a track relay at each end of the stretch which is responsive to unidirectional current periodically interrupted, a manually controlled directional means for establishing the direction of traffic to connect the track relay to the rails at the entrance end of the stretch for the direction established and to render the current source effective to supply said periodically interrupted current to the rails at the exit end 75 for the said direction of traffic, traffic controlled means to select the different rates of the interrupted current in accordance with traffic conditions, a plurality of decoding relays associated with each track relay, means to selectively energize said decoding relays in accordance with the rate of the interrupted current with which the track relay is operated, and means controlled by said decoding 80 relays to govern the operation of the signals.

3. In a combined wayside and cab signal system including a stretch of track rails over which traffic may move in either direction, a wayside signal located at each end of the stretch to govern traffic in opposite directions through the stretch, a current source for each direction of traffic located at opposite ends 95 of the stretch each capable of supplying to the rails unidirectional current periodically interrupted at different rates which are adaptable to control train carried cab signals, directional means for establishing the direction of traffic to render the current source associated with the direction of traffic selected effective to supply said interrupted current, traffic controlled means to select the different rates of the interrupted unidirectional current 100 in accordance with traffic conditions, a trackway means connected to the rails and selectively responsive to the different rates of interruptions of said unidirectional current in the rails to control the wayside signals, and a manually controlled means to control 105 the directional means.

4. In a combined wayside and cab signal system including a stretch of track rails over which traffic may move in either direction, a wayside signal located at each end of the stretch to govern traffic in opposite directions through the stretch, a current source for each direction of traffic located at opposite ends of the stretch each capable of supplying to the rails current periodically interrupted at different rates and which are adaptable to control train-carried cab signals, directional means for establishing the direction of traffic and to render the current source associated with the direction of traffic 110 115 120 125 130

selected effective to supply said interrupted current, traffic controlled means to select the different rates of the interrupted current in accordance with traffic conditions, a trackway means connected to the rails and selectively responsive to the different rates of interruptions of the periodically interrupted current to control the wayside signals, and a manually controlled means to control the directional means.

5. In a manually controlled wayside and cab signal system including, a stretch of track rails over which traffic may move in either direction, a wayside signal located at

15 each end of the stretch to govern traffic in opposite directions through the stretch, a current source for each direction of traffic located at opposite ends of the stretch each capable of supplying to the rails coded current

20 of different codes and which are adaptable to control train-carried cab signals, directional means for establishing the direction of traffic and to render the current source associated with the direction of traffic established

25 effective to supply said coded current, traffic controlled means to select the different codes of the current in accordance with traffic conditions, a trackway means selectively responsive to the different codes to control the wayside signals, and a manually controlled means to control said directional means.

6. In a wayside and cab signal system including, traffic rails over which traffic may move in either direction arranged in track

35 sections, a wayside signal located at each end of a section to govern traffic in opposite directions through the section, a current source located at each end of a section each capable of supplying to the rails unidirectional current

40 periodically interrupted at different rates and which are adaptable to control train-carried cab signals, a manually controlled directional relay for each section to select the direction of traffic and to render either one or the other of the current sources

45 effective to supply said interrupted current, a track relay for each section connected to the rails and responsive to unidirectional current periodically interrupted, a plurality of de-

50 coding relays for each section, means associated with each track relay to selectively energize said decoding relays in accordance with the rate of the interrupted current with which said track relay is operated, means

55 controlled by said decoding relays to determine the rate of the interrupted current supplied to the rails of the section next in the rear for the direction for which traffic has been selected in accordance with the conditions of the decoding relays, and other means controlled by the decoding relays to govern the wayside signals.

7. In a combined wayside and cab signal system including, traffic rails over which traffic may move in either direction arranged

in track sections, a wayside signal located at each end of a section to govern traffic in opposite directions through the section, a current source located at each end of a section each capable of supplying to the rails unidirectional current periodically interrupted at different rates and which are adaptable to control train-carried cab signals, a manually controlled directional relay for each section to select the direction of traffic and to render either one or the other of the current sources effective to supply said interrupted unidirectional current, a track relay for each section connected to the rails and responsive to unidirectional current periodically interrupted, a plurality of decoding relays for each section, means associated with each track relay to selectively energize said decoding relays in accordance with the rate of the interrupted current with which said track relay is operated, and means controlled jointly by the directional relay and the decoding relays to control the interrupted current supplied to the rails of the section next in the rear for the direction for which traffic has been selected and to govern the wayside signals.

8. In a combined wayside and cab signal system including, a stretch of track rails arranged in track sections, a wayside signal for each section to govern traffic through the section, a current source located at the exit end of each section capable of supplying to the rails coded current of different codes which are adaptable to control train-carried cab signals, traffic controlled means for each section to select the different codes of the coded current in accordance with traffic conditions in advance of the section, trackway means for each section connected to the rails and selectively responsive to the different codes of said coded current to govern the wayside signal, and means for each section controlled manually from a distant point to render the current source effective to supply said coded current.

9. In a combined wayside and cab signal system including, a stretch of track rails arranged in track sections, a wayside signal for each section to govern traffic through the section, a current source located at the exit end of each section capable of supplying to the rails unidirectional current periodically interrupted at different rates and which are adaptable to control train-carried cab signals, traffic controlled means to select the different rates of interruptions of the periodically interrupted current in accordance with traffic conditions in advance of the section, trackway means for each section connected to the rails at the entrance end and selectively responsive to the different rates of interruptions of the interrupted current to govern the wayside signal, and means for each section controlled manually from a distant point to render the current source effective to sup-

ply said periodically interrupted unidirectional current.

10. In a combined wayside and cab signal system including, a stretch of track rails arranged in track sections, a wayside signal for each section to govern traffic through the section, a current source located at the exit end of each section capable of supplying to the rails unidirectional current periodically interrupted at different rates and which are adaptable to control train-carried cab signals, a track relay for each section connected to the rails at the entrance end and responsive to the periodically interrupted unidirectional current, a plurality of decoding relays for each section, means associated with each track relay to selectively energize said decoding relays in accordance with the rate of the interrupted current with which said track relay is operated, means controlled by the decoding relays for governing the signal and to determine the rate of the interrupted current supplied to the rails of the section next in the rear, and means for each section controlled manually from a distance point to render the current source effective to supply said periodically interrupted unidirectional current.

11. In combination, traffic rails arranged in track sections, a source of current for each section adapted to supply to the traffic rails rectified alternating current periodically interrupted at different rates, a track relay for each section connected to the rails and responsive to periodic interruptions of rectified alternating current in the rails, a plurality of decoding relays for each section, means associated with each track relay for selectively energizing said decoding relays in accordance with the rate of the interrupted current with which the track relay is operated, and means controlled by the decoding relays for controlling the source of current for the next section in the rear arranged to select different rates of periodic interruptions of said rectified alternating current in accordance with the conditions of the decoding relays.

12. In combination, traffic rails arranged in track sections, a source of current for each section adapted to supply to the traffic rails rectified alternating current periodically interrupted at different rates, a track relay for each section connected to the rails and responsive to periodic interruptions of rectified alternating current in the rails, a plurality of decoding relays for each section, means associated with each track relay for selectively energizing said decoding relays in accordance with the rate of the interrupted current with which the track relay is operated, means controlled by the decoding relays for controlling the source of current for the next section in the rear arranged to select different rates of periodic interruptions of said rectified alternating current in

accordance with the condition of the decoding relays, and signals for the section controlled by the said decoding relays.

13. In combination, traffic rails arranged in track sections, a source of current for each section adapted to supply to the traffic rails unidirectional current periodically interrupted at different rates, a track relay for each section connected to the rails responsive to periodic interruptions of unidirectional current in the rails, a plurality of decoding relays for each section, means associated with each track relay for selectively energizing said decoding relays in accordance with the rate of the interrupted current with which the track relay is operated, a control relay for each section controlled manually from a distant point, and circuit means controlled jointly by said control relay and said decoding relays for controlling the source of current for the next section in the rear arranged to select different rates of periodic interruptions of said unidirectional current in accordance with the conditions of the said relays.

14. In combination, traffic rails arranged in track sections, a track transformer for each section having its secondary winding connected to the traffic rails, means to supply the primary winding of each transformer with coded alternating current of different codes, means associated with the secondary winding of each track transformer to convert the coded alternating current into coded unidirectional current, a track relay for each section responsive to coded unidirectional current in such rails, a plurality of decoding relays for each section, means associated with each track relay to selectively energize said decoding relays in accordance with the code operating the track relay, means controlled by the decoding relays for controlling the coded alternating current supplied to the primary of the track transformer of the next section to the rear arranged to select the different codes in accordance with the conditions of the decoding relays, and signals for the section controlled by the said decoding relays.

15. In combination, a stretch of railway over which traffic may move in either direction arranged into track sections, a source of current located at opposite ends of each track section each capable of supplying to the rails coded current of different codes, a track relay located at each junction of adjacent track sections capable of being connected to the rails of either track section and responsive to coded current, a manually controlled traffic directional means located at each junction of adjacent track sections to connect the track relay to the rails of the section which for the direction of traffic established has its entrance end at this junction, and to render effective the source of current located at the exit end of a section for the direction of traf-

fic established effective to supply said coded current, a plurality of decoding relays associated with each track relay, means to selectively energize said decoding relays in accordance with the code operating the track relay, and two signals located at each junction of adjacent track sections to govern traffic in opposite directions and selectively controlled jointly by the traffic directional means and the decoding relays.

16. In combination, a stretch of railway over which traffic may move in either direction arranged into track sections, two sources of current located at each junction of adjacent track sections each capable of supplying to the rails of a respective track section unidirectional current periodically interrupted at different rates, a track relay located at each junction of adjacent track sections capable of being connected to the rails of either track section and responsive to periodic interruptions of unidirectional current, a manually controlled traffic directional means located at each junction of adjacent track sections to connect the track relay to the rails of the section which for the direction of traffic established has its entrance end at this junction and to render the source of current for the section having its exit end at this junction effective to supply said interrupted current, a plurality of decoding relays associated with each track relay, means to selectively energize said decoding relays in accordance with the rate of the interrupted current operating the track relay, two signals located at each junction of adjacent track sections to govern traffic in opposite directions, and means controlled jointly by the traffic directional means and the decoding relays to selectively govern said signals and to select the rate of interruptions of the unidirectional current supplied by the active source of current rendered effective at that junction.
17. In combination, a stretch of railway track, a signal for governing traffic movements in a given direction in said stretch, a second signal for governing traffic movements in a second direction in said stretch, an approach control relay, manually controlled apparatus for at times causing said relay to be controlled by a train approaching said first signal in said first direction and for at other times causing said relay to be controlled by a train approaching said second signal in said second direction, and means controlled by said relay for controlling said first and second signals.
18. In combination, a stretch of railway track, a light signal for governing traffic movements in a given direction in said stretch, a second light signal for governing traffic movements in the opposite direction in said stretch, a normally energized approach lighting relay, manually controlled

apparatus for at times putting said relay in condition to be deenergized by a train approaching said first signal in said given direction and for at other times putting said relay in condition to be deenergized by a train approaching said second signal in the opposite direction, and means for causing said first and second signals to be lighted if and only if said relay is deenergized.

19. In combination, a stretch of railway track divided into sections, an eastbound track circuit for each section controlled by unidirectional current periodically varied according to a plurality of codes, a westbound track circuit for each section controlled by unidirectional current periodically varied according to a second plurality of codes, means controlled by the eastbound track circuits for controlling eastbound traffic movements according to said first plurality of codes, and means controlled by the westbound track circuits for controlling westbound traffic movements according to said second plurality of codes.

20. In combination, a stretch of railway track, an eastbound track circuit for said stretch controlled by unidirectional current, a westbound track circuit for said stretch including a part of said eastbound track circuit, and controlled by unidirectional current periodically varied according to a plurality of codes, means controlled by the eastbound track circuit for controlling eastbound traffic movements in said stretch, and means controlled by the westbound track circuit for controlling westbound traffic movements in said stretch according to said codes.

21. In combination, a stretch of railway track, an eastbound track circuit for said stretch controlled by unidirectional current periodically varied according to a plurality of codes, a westbound track circuit for said stretch including a part of said eastbound track circuit and controlled by unidirectional current periodically varied according to a second plurality of codes, means controlled by the eastbound track circuit for controlling eastbound traffic movements in said stretch according to said first plurality of codes, and means controlled by the westbound track circuit for controlling westbound traffic movements in said stretch according to said second plurality of codes.

22. In combination, a stretch of railway track, manually controlled apparatus, means controlled by said apparatus for supplying periodically varied current to the rails of said stretch for controlling traffic movements in a given direction in said stretch, and means controlled by said apparatus for supplying periodically varied current to the rails of said stretch for controlling traffic movements in the opposite direction in said stretch.
